METHOD OF FORMING VARIEGATED SURFACE COVERINGS

J. Clarence McCarthy, Manheim Township, Lancaster County, Pa., assignor to Armstrong Cork Company, Lancaster, Pa., a corporation of Pennsylvania

Application November 15, 1949, Serial No. 127,386

4 Claims. (Cl. 18—48.8)

1

This invention relates to a method of forming variegated surface coverings and is concerned particularly with the formation of products of linoleum or the like having a marbleized graining.

In the manufacture of linoleum, rubber tile, asphalt tile, and other plastic surface coverings, it is common to variegate the composition and form it into sheets or tiles having a veined or grained appearance in simulation of marble or the like. Such graining is commonly obtained in linoleum by mixing granules of base and variegating color compositions and feeding these as a mass into a calender. This forms a sheet having a veined appearance in which the graining is disposed generally parallel to the length of the sheet. The sheets thus formed are severed into sections which are fed in overlapping cross-rolling relationship to a second calender which consolidates the sheets into a single thickness and forms a sheet having a marbleized appearance. This requires the hand feeding of the overlapped sheets to the cross-rolling calender, and there is some tendency to form objectionable graining disfigurement where adjacent sheets overlap as they pass through the calender.

An object of the present invention is to provide a simplified method of making variegated surface coverings having a grained appearance which may be accomplished fully automatically.

Another object of the invention is to provide a method which will produce a novel type of graining without objectionable lines of demarcation such as are encountered in the conventional marbleizing processes now in use where overlapped sheets are cross-rolled.

Other objects of the invention will become apparent from a consideration of the following detailed description of certain preferred embodiments of this invention. These will be described in conjunction with the attached drawings in which:

Figure 1 is a perspective view of a rod of color compositions;

Figure 2 is a perspective view showing the rod of Figure 1 severed into pellets;

Figure 3 is a plan view of a waferlike piece formed from one of the pellets of Figure 2, the left-hand portion of Figure 3 showing one surface of the waferlike piece and the right-hand portion showing the opposite surface of the piece;

Figure 4 is a plan view showing one surface of a waferlike piece formed from a generally spherical pellet of base and variegating color compositions;

2

Figure 5 is a plan view showing a plurality of generally spherical pellets of the type used in the formation of the waferlike piece of Figure 4;

Figure 6 is a diagrammatic view illustrating apparatus useful in the practice of the method;

Figure 7 is a diagrammatic view of a portion of one of the conveyor belts used in the apparatus of Figure 6 for conveying individual pellets; and

Figure 8 is a plan view illustrating the graining effect obtained by the practice of the invention.

The invention is applicable to various types of surface coverings, including linoleum, rubber compositions, asphalt compositions of the type commonly employed in the production of floor and wall coverings, so-called synthetic resin type plastic compositions, and the like. The invention finds particular usefulness in the manufacture of surface coverings of linoleum and rubber compositions. The linoleum composition type will be taken as typical in the description of certain embodiments of the invention which follows.

25 A batch of linoleum composition of a desired base color is prepared in the conventional manner and formed into a generally free flowing granulated mass. A plurality of batches of linoleum composition of variegating colors are prepared, and measured quantities of the variegating color compositions are discharged into a mottler with the base color composition, and the base and variegating color compositions are thoroughly intermingled. The intermingled mass is then formed into pellets. This may be accomplished by compacting charges of the mass of base and variegating color compositions into cylindrical rods such as the one indicated at 2 in Figure 1. It will be observed that the base color composition 3 and the variegating color compositions 4, 5, and 6 are generally disposed as individual, visually discernible granules throughout the body of the rod 2, although there may be some striation of the granules at the outer surface of the rod as indicated at 7 in Figure 1 caused by relative movement between the mass and the forming surface during the production of the rods. Linoleum composition is coherent when consolidated under pressure, and thus the rod 2 is self-supporting and may be cut into pieces as indicated at 8 in Figure 2. Saws or cutting knives may be employed.

The size of the rods and the pieces may vary over a considerable range. As a typical example, the pieces may be about 1" in diameter and $\frac{3}{8}$ " in axial length or thickness.

The individual pellets are compressed into thin, flat, waferlike pieces as indicated in Figure 3. This is preferably accomplished by passing the pellets individually through a pair of small calendering rolls which are spaced apart a distance approximately equivalent to the thickness desired in the final waferlike pieces. In the typical embodiment chosen for illustration, the pellets 8 may be reduced to about $\frac{1}{8}$ " thickness; and, where calendering is employed to form the pieces, they will be about 3 to $3\frac{1}{2}$ " long by about 2" wide at the line of maximum width and generally elliptical in shape as indicated in Figure 3. One side 9 of the waferlike pieces will have a graining similar to that shown in Figure 3, and the opposite side 10 will have a graining which includes a border portion 11 formed from the outer surface 12 of the pellet 8 and a central portion 13 which will be grained but not to the extent of the upper surface 9.

The thin, flat, waferlike pieces are next consolidated into a sheet. This is preferably accomplished by feeding the pieces as a heterogeneous bank into a pair of calender rolls with some of the pieces disposed with their graining at an angle to the direction of calendering and with the faces 9 and 10 randomly arranged with respect to the calender rolls. Reference to Figure 8 indicates diagrammatically as accurately as possible the type of graining obtained by the calendering operation upon the heterogeneous bank of pieces. It will be noted that the graining 14 is nondirectional and relatively fine lined.

Figure 6 illustrates diagrammatically apparatus which may be used in the practice of the method of the invention. The pellets 15 are charged into a plurality of hoppers 16 which are provided with brushes 17, the purpose of which is to orient the pellets on conveyors 18 in a desired spaced relationship. This may be facilitated by providing the conveyor 18 with openings 19 as shown in Figure 7 and providing suction boxes 20 below the inclined run of the conveyors as indicated at Figure 6 to hold the individual pellets on the conveyor 18 in spaced relationship, one pellet being held above each of the openings 19. The right-hand conveyors and hoppers are not shown completely in Figure 6. They may be the same as shown in the left-hand portion of the figure. The individual pellets are fed into pairs of small calendering rolls 21, one pair being provided for each conveyor. These rolls 21 are effective for reducing the pellets to the thin, waferlike pieces shown in Figure 3. It is desirable to form the pieces individually, and for that reason, it is essential that the delivery of the pieces be spaced in time so that the waferlike pieces which are formed are separate and distinct and not connected together as would occur if a mass of the pellets were fed to the consolidating rolls.

The pieces 22 thus formed are fed as a heterogeneous bank 23 into the nip between a pair of rolls of a sheeting calender 24. This calender 24 consolidates the pieces into a sheet which may be of any desired width and thickness. In the embodiment chosen for illustration, the sheet formed may be about $\frac{1}{8}$ " thick by 72" wide and of indefinite length.

The number of pairs of calender rolls 21 employed will depend upon the rate of production of the calender 24. It is possible, of course, to form the waferlike pieces in advance and feed them to the calender, but the preferred practice is to operate the process continuously by supplying the pellets to the consolidating rolls at a rate

which approximates the rate of production of the calender 24. Since the pieces are formed individually, it is necessary in order to attain a high-speed production on the calender 24 as a continuous process to provide a plurality of calenders 21 or their equivalent for forming the waferlike pieces.

It will be noted by reference to Figure 6 that the pieces are randomly or heterogeneously disposed in the bank 23 and that the bank consists essentially wholly of the waferlike pieces. Some of the pieces are disposed with their graining parallel to the axis of the calender 24 and others are arranged at other angles with respect thereto. Some of the pieces have their faces 9 disposed in one direction and others in an opposite direction. Thus the graining produced has an unusual character and is pleasing in its absence of a definite repeat.

Instead of forming the pellets in the manner described in connection with Figures 1, 2, and 3, waferlike pieces 25, as shown in Figure 4, may be prepared by consolidating the base and variegating color compositions in granular form into pellets 26, as shown in Figure 5, which are generally spherical. These pellets may be formed on a conventional pilling machine and may be in the order of 1" in diameter and about $1\frac{1}{4}$ " long. When these pills are individually consolidated, they produce an irregularly shaped, waferlike piece having a surface graining which is generally the same as shown in Figure 3, although there will be no outer border similar to the portion 11, for the granules will not be substantially striated at the surface of the pellets. The pellets may be formed into the waferlike sheets by consolidating rolls similar to the rolls 21 and the pieces thus formed fed as a heterogeneous bank to a calender.

Where linoleum in sheet form is produced, common practice is to form the sheet directly upon a suitable backing such as burlap or a waterproofed felt. Where tile pieces are prepared, the backing may be removed subsequent to curing of the composition. In rubber tile manufacture the sheets produced on the calender 24 will be vulcanized, generally without a backing and subsequently cut into pieces of the desired size and shape. The process does not differ in any essential regard with either practice. If a backing is employed, it will generally be fed over one of the calender rolls, and the material will be consolidated upon the backing at the nip between the calender rolls.

The process of this invention may be practiced continuously with a minimum of labor, and the problem of objectionable distortion of the graining is obviated. The process produces an attractive graining which simulates marble and may be varied to a substantial extent by alterations in the size of the granules used, the size and shape of the pellets, the thickness of the waferlike pieces, the degree of consolidation in final sheet formation, and the like.

I claim:

1. In a method of forming a variegated surface covering, the steps comprising forming coherent pellets made up of a mixture of individual, visually discernible granules of base and variegating color compositions with the color compositions intermingled throughout the pellets, feeding the pellets individually into consolidating rolls where they are formed into separate and individual, thin, flat, waferlike pieces with a grained appearance extending generally along

the direction of rolling of the pieces, feeding a mass consisting substantially wholly of the waferlike pieces as a heterogeneous bank into a calender with some of said waferlike pieces having their flat faces disposed parallel to the axis of the calender, others at right angles thereto, and still others disposed at other angles with respect to said axis, and consolidating them into a variegated sheet.

2. In a method of forming a variegated surface covering, the steps comprising forming coherent pellets made up of a mixture of individual, visually discernible granules of base and variegating color compositions with the color compositions intermingled throughout the pellets, feeding the pellets individually into consolidating rolls where they are formed into separate and individual, thin, flat, waferlike pieces with a grained appearance extending generally along the direction of rolling of the pieces, feeding a mass consisting substantially wholly of the waferlike pieces as a heterogeneous bank into a calender with some of said waferlike pieces having their flat faces disposed parallel to the axis of the calender, others at right angles thereto, and still others disposed at other angles with respect to said axis and with some of the pieces disposed with their graining at different angles to the direction of calendering, and consolidating the pieces into a variegated sheet.

3. In a method of forming a variegated surface covering, the steps comprising forming a mixture of individual, visually discernible granules of base and variegating color compositions into coherent rounded pellets with the color compositions intermingled throughout the pellets, calendering the pellets individually into separate and individual, thin, flat, waferlike pieces having a grained appearance extending generally along the direction of the calendering of the pieces,

feeding a mass consisting substantially wholly of the waferlike pieces so formed as a heterogeneous bank into a calender with some of said waferlike pieces having their flat faces disposed parallel to the axis of the calender, others at right angles thereto, and still others disposed at other angles with respect to said axis and with some of the pieces disposed with their graining at an angle to the direction of initial calendering, and consolidating the pieces into a variegated sheet.

4. In a method of forming a variegated surface covering, the steps comprising intermingling individual, visually discernible granules of base and variegating color compositions to form a mass in which the color compositions are intermingled together, forming compressed and coherent pellets of the intermingled granules, calendering the pellets individually into separate and individual, thin, flat, waferlike pieces with a grained appearance extending generally along the direction of the calendering of the pieces, feeding a mass consisting substantially wholly of the waferlike pieces as a heterogeneous bank into a calender with some of said waferlike pieces having their flat faces disposed parallel to the axis of the calender, others at right angles thereto, and still others disposed at other angles with respect to said axis, and consolidating the same into a variegated sheet having a nondirectional graining.
